CLAIM

We claim the ornamental design for a data cable connector, as shown and described.

DESCRIPTION

FIG. 1 is a front perspective view of a data cable connector in a retracted state showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a data cable connector in an extended state showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is a rear perspective view thereof; and,

FIG. 17 is a rear perspective view of the data cable connector shown in a state of use, in which the claimed design is shown connected to an electronic device.

The broken lines in the figures depict environmental subject matter and portions of the data cable connector which form no part of the claimed design.
